GLOVE

George T. Corombos, Iron Mountain, Mich.

Application March 25, 1932. Serial No. 601,212

3 Claims. (Cl. 2—159)

This invention relates to improvements in gloves, the general object of the invention being to provide at reduced cost a glove which may be worn on either hand.

This invention also comprises in certain other features of construction and in the combination and arrangement of the several parts to be hereinafter fully described, illustrated in the accompanying drawings, and specifically pointed out in the appended claims.

In describing the invention in detail, reference will be had to the accompanying drawings wherein like characters denote like or corresponding parts throughout the several views, and in which:—

Figure 1 is a plan view of one side of the glove.

Fig. 2 is a plan view of the opposite side of the glove.

Fig. 3 is a plan view of the blank from which the major part of the glove is formed.

Fig. 4 is a plan view of a rectangular sheet which forms the palm part of one side of the glove.

Fig. 5 is a plan view of one side of the thumb stall.

Fig. 6 is a plan view of the piece used to complete the middle finger stall of that side of the glove shown in Fig. 2.

Fig. 7 is a plan view of the piece used to complete the third finger stall at the side of the glove shown in Figure 2.

In these drawings, the letter A indicates the blank from which is constructed one side of the glove and parts of the opposite side. The blank A is provided with three parallel cuts 1 made inwardly from its upper edge to define sections a, b, c, d, whose outer ends are rounded as shown. Wings 2 and 2' at opposite side edges of the blank A are arranged to be folded on the parallel lines 3, 3. The wings are generally similar in form but the wing 2 is slightly wider than the wing 2'.

An elongated opening 4 is formed in the blank A on the right hand line 3 close to the lower edge of the blank, so that when the wing is folded on this line 3, this opening 4 will be partly at one side and partly at the opposite side of the glove. The thumb stall designated 5 is composed of two similar sections sewn together at the edges but leaving the lower end open. The edges of the thumb stall opening are sewn to the edges of the opening 4. Thus the thumb stall is made to extend from one edge of the glove equally on either side of the glove, so that it is free to be swung

equally in either direction so that the glove may be conveniently worn on either hand. A substantially rectangular piece 6 has its side edges fastened to the outer edges of the lower narrower portions of the wings 2 and 2' as shown in Figure 2 at 6'.

The "little" finger stall is formed by folding over the wider upper portion of the part 2 onto the section d and subsequently sewing together the corresponding edges.

The third finger stall is formed by superposing the separate piece 8 on the section c and sewing together the corresponding edges.

The middle finger stall is formed by superposing the separate piece 7 upon the section b and sewing the corresponding edges together.

The index finger stall is formed by folding the upper wider portion of the wing 2' onto the section a and sewing the corresponding edges together.

The rectangular palm part 6 is then sewed at its top edge to the lower edges of the separate pieces 7 and 8, and at its side edges to the outer edges of the wings 2 and 2'.

The upper edge of the wrist part 9 is secured to the lower edge of the rectangular piece 9 and to the lower edge of the wings 2, 2' on one side of the glove and to the lower edge of the other side of the glove.

It is thought that the advantages and novel features of the invention will be readily apparent from the foregoing description.

It is to be understood that changes may be made in the construction and in the combination and arrangement of the several parts provided that such changes fall within the scope of the appended claims.

Having thus described my invention what I claim as new is:—

1. A glove to be worn on either hand, said glove comprising a flat envelope open at one end and closed at the other, one side of the envelope comprising a sheet provided with cuts from its upper edge defining an index finger stall section, a middle finger stall section, and a "little" finger stall section; the remaining side of the envelope comprising an extension of one side edge of the first side and folded so as to impose a portion thereof on and sewed to the "little" finger section to form the little finger stall, a second and generally similar extension of the opposite side edge of the first side and folded so as to impose a portion thereof upon and sewed to the index finger section to form the index finger stall; a relatively large generally rectangular palm sheet interposed

between and having opposite side edges sewed to the lower portion of the inward edges of the extensions; a separate piece imposed upon and sewed at the one end and at the sides edges to the third finger stall section, a second separate piece imposed upon and sewed at one end and at the side edges to the middle finger stall section; the upper edge of the palm sheet being sewed to the lower edges of the separate sections; and a thumb stall having its opening sewed to the edges of a vertical opening on the folding line of the first extension, so as to extend equally on either side of the envelope.

2. A glove to be worn on either hand, said glove comprising a generally rectangular sheet having cuts inward of its upper edge defining an index finger section, a middle finger section, a third finger section, and a "little" finger section; a wing on one side edge of the sheet folded upon the sheet and having a portion sewed to the index finger section to form the index finger stall, a second wing on the opposite side edge of the sheet and folded upon the sheet and having a portion sewed to the "little" finger section to form the "little" finger stall; a separate conforming piece sewed to the middle finger section to form the middle finger stall, a second separate conforming piece sewed to the third finger section to form the third finger stall; a relatively large rectangular palm piece having its upper edge sewed to the lower edge of the first and second separate pieces, and its side edges sewed to the remaining portion of the inward edges of the wings; a thumb stall having the edges of its opening sewed to the

edges of a vertical opening on the folding line of the first wing so as to be disposed equally on opposite sides of the glove, and a wrist portion sewed to the lower edges of the palm piece, the wings and to the lower edge of the sheet so as to assist in holding the same in alignment.

3. A glove to be worn on either hand, said glove comprising a generally rectangular sheet having cuts inward of its upper edge defining an index finger section, a middle finger section, a third finger section, and a "little" finger section; a wing on one side edge of the sheet folded upon the sheet and having a portion sewed to the index finger section to form the index finger stall, a second wing on the opposite side edge of the sheet and folded upon the sheet and having a portion sewed to the "little" finger section to form the "little" finger stall; a separate conforming piece sewed to the middle finger section to form the middle finger stall, a second separate conforming piece sewed to the third finger section to form the third finger stall; a relatively large rectangular palm piece having its upper edge sewed to the lower edge of the first and second separate pieces, and its side edges sewed to the remaining portion of the inward edges of the wings; and a thumb stall having the edges of its opening sewed to the edges of a vertical opening on the folding line of the first wing so as to be disposed equally on opposite sides of the glove, said thumb stall being formed of a pair of similar pieces sewed together at one end and the side edges.
